(57) **CLAIM**

I claim the ornamental design for a chair, as shown and described.

DESCRIPTION

FIG. 1 is a perspective view of the chair of a new design;

FIG. 2 is a top view of the chair of FIG. 1;

FIG. 3 is a front view of the chair of FIG. 1;

FIG. 4 is a left side view of the chair of FIG. 1;

FIG. 5 is a rear view of the chair of FIG. 1;

FIG. 6 is a right side view of the chair of FIG. 1; and,

FIG. 7 is a bottom view of the chair of FIG. 1.

The broken lines shown in the drawings are for environmental purposes only and form no part of the claimed design.
